UNITED STATES PATENT OFFICE.

MASON COMBS, OF PINEVILLE, KENTUCKY.

STOPPER.

Application filed September 27, 1922. Serial No. 590,868.

To all whom it may concern:

Be it known that I, MASON COMBS, citizen of the United States, residing at Pineville, in the county of Bell and State of Kentucky, ⁵ have invented certain new and useful Improvements in Stoppers, of which the following is a specification.

This invention relates to an improved stopper for bottles or other containers, being ¹⁰ particularly designed for use by druggists, doctors or the like, and seeks, as one of its principal objects, to provide a stopper which, without removing or dislocating the stopper, may be adjusted within the neck of a bottle ¹⁵ to regulate the discharge of the contents of the bottle in drops.

A further object of the invention is to provide a stopper which may be adjusted for dropping heavy or viscous fluids as well as ²⁰ lighter fluids.

And the invention has as a still further object to provide a stopper wherein any given fluid may be dropped in uniform drops.

²⁵ Other and incidental objects will appear hereinafter.

In the drawings:

Figure 1 is a fragmentary sectional view showing my improved stopper in connection ³⁰ with an ordinary bottle,

Figure 2 is a sectional view on the line 2-2 of Figure 1, looking in the direction of the arrows,

Figure 3 is a view showing the stopper ³⁵ adjusted for dropping,

Figure 4 is a sectional view on the line 4-4 of Figure 3, looking in the direction of the arrows,

Figure 5 is a fragmentary sectional view ⁴⁰ showing the stopper adjusted for dropping viscous or heavy fluids,

Figure 6 is a perspective view of the stopper as illustrated in Figure 5,

Figure 7 is a fragmentary sectional view ⁴⁵ showing a slight modification of the invention,

Figure 8 is a sectional view on the line 8-8 of Figure 7, looking in the direction of the arrows,

Figure 9 is a fragmentary sectional view ⁵⁰ showing the closed position of the stopper,

Figure 10 is a transverse sectional view on the line 10-10 of Figure 9, looking in the direction of the arrows,

Figure 11 is a sectional view similar to ⁵⁵ Figure 10, showing the manner in which the sections of the stopper may be adjusted for dropping different fluids, and

Figure 12 is a detail perspective view of the modified construction. ⁶⁰

In carrying the invention into effect, I employ a longitudinally tapered stopper body which is split transversely near the inner end thereof into companion sections 10 and 11 respectively. The stopper body ⁶⁵ may be formed of cork, rubber or other approved material and extending axially through the sections of the body is a rod 12 rotatably connecting the sections. This rod may be of metal or, if preferred, may be ⁷⁰ of glass so as to resist the action of acids and secured upon the ends of the rod are heads 13 for sustaining endwise pull upon the stopper. As best shown in Figure 6, the sections 10 and 11 of the stopper body are ⁷⁵ cut away to provide flat faces 15 and 16 and formed in each of said faces is a pair of longitudinally directed grooves, the grooves in the face 15 of the section 10 being indicated at 17 and the grooves in the face 16 of the section 11 being indicated at 18. As will be observed, the sections may be rotated relative to each other to dispose the flat faces 15 and 16 thereof in alinement ⁸⁰ when the grooves 17 will register with the 18. ⁸⁵

In the drawings, I have, in order to clearly bring out the manner of operation of my improved stopper, shown the device in connection with an ordinary bottle 19. In ⁹⁰ use, the stopper is, as shown in Figure 1, forced into the neck of the bottle in the usual manner when, by rotating the section 10 of the stopper body relative to the section 11 thereof until the flat faces 15 and 16 of said sections are disposed opposite each other, the sections will cooperate for closing the bottle in the manner of an ordinary stopper, it being observed in this connection, that the section 11 of the stopper body will be frictionally held against rotation within the neck of the bottle so that the section 10 may be turned individually. For the purpose of dropping the contents of the bottle therefrom, the section 10 of the stopper body is, as shown in Figures 3 and 4, turned until the planes of the faces 15 and 16 of the sections of the body are brought ⁹⁵ ¹⁰⁰ ¹⁰⁵

into intersecting relation to define a passage at the adjacent side of the stopper and, of course, the section 10 may be rotatably adjusted for varying the cross sectional area 5 of said passage. Accordingly, the section 10 may be set for any given fluid so that the fluid will issue from said passage in drops of uniform size and by turning the section until one of the grooves 17 of said 10 section is brought into registration with one of the grooves 18 of the section 11, a channel will be provided at the adjacent side of the stopper whereby the capillary force of the fluid in said channel may overcome atmospheric pressure to permit the contents of the 15 bottle to be dropped therefrom even though the bottle is full. For dropping heavy or viscous fluids, the section 10 of the stopper body is turned to the position shown in 20 Figures 5 and 6 of the drawings, when the flat faces 15 and 16 of the sections of the stopper body will be disposed in alinement while the grooves 17 and 18 will register. A relatively large passage will thus be defined at the adjacent side of the stopper body through which the contents of the bottle may issue in drops of uniform size.

In Figures 7 to 12 inclusive, I have illustrated a slight modification of the invention 30 wherein I employ a longitudinally tapered stopper body split near its inner end into companion sections 20 and 21 respectively. Rotatably connecting the sections is an axially disposed rod 22, as in the preferred 35 construction, and formed in the section 20 at opposite sides thereof are oppositely disposed longitudinal grooves 23 while the section 21 is provided with similar oppositely disposed grooves 24. For convenience, I 40 have shown the modified stopper in conjunction with an ordinary bottle 25, the stopper being formed to engage in the neck of the bottle in the manner of an ordinary stopper.

As will now be seen, the outer section 20 45 may, as shown in Figure 7, be turned with respect to the inner section 21 of the stopper body to dispose the grooves 23 of the former section in register with the grooves 24 of the latter section. Passages will thus be defined at opposite sides of the stopper and in use, the bottle is preferably so held that one of said passages will be disposed downwardly while the other of said passages will be disposed upwardly. Accordingly, since, 50 when the bottle is so held, the fluid within the bottle will offer less resistance to atmospheric pressure at the upper passage than at the lower passage, air will enter the bottle through the upper passage so that the 55 contents of the bottle may be dropped therefrom through the lower passage in drops of uniform size occurring at regular intervals. The grooves are preferably of such size that heavy or viscous fluids will readily flow therethrough and, by adjusting the outer 60

section of the stopper body with respect to the inner section thereof, the grooves 23 may, as suggested in Figure 11, be moved more or less out of register with the grooves 21 of the inner section of the stopper body 70 for reducing the flow through said grooves. Accordingly, the stopper may be readily set for dropping drops of different sizes or for dropping liquids of light specific gravity. To close the bottle, the section 20 of the stopper is, as shown in Figure 10, turned until the grooves therein are disposed completely out of register with the grooves in the section 21, when the sections will cooperate to 75 seal the bottle.

Having thus described the invention, what is claimed as new is:

1. A stopper including a stopper body formed of complemental sections having flat faces, and means independent of the sections extending therethrough and connecting the sections for relative rotation whereby said faces may be disposed to define a fluid outlet passage. 80

2. A stopper including a stopper body formed of complemental sections provided with angular side faces having grooves therein, and means connecting the sections for relative rotation whereby said faces may be disposed to define a fluid outlet passage 90 while said grooves may be brought into registration to define a channel at said passage. 95

3. A stopper including a stopper body formed of complemental sections provided with flat side faces having grooves therein, and means connecting the sections for relative rotation whereby said faces may be disposed to define a fluid outlet passage while 100 said grooves may be brought into registration defining a channel at said passage. 105

4. A stopper comprising coacting body sections, and means rotatably connecting the sections in mating relation to form a stopper body insertable in a bottle neck to frictionally engage the sections thereof with the inner surface of the neck, normally cooperating with each other and with the inner surface of the neck to form a closed joint lying between the ends of the neck, the sections having fluid outlets and one of said sections being rotatable to dispose said outlets in communication. 110

5. A stopper comprising tapered body sections, and means rotatably connecting the sections in mating relation to form a stopper body tapered from end to end for insertion in a bottle neck to frictionally engage the sections thereof with the inner surface of the neck, normally cooperating with each other and with the inner surface of the neck to form a closed joint lying between the ends of the neck, said sections being provided with fluid outlets and one of the sections being rotatable to dispose said outlets in communication. 120 125 130

6. The combination with a fluid container having a neck, of a sectional stopper having the sections thereof fitting in said neck frictionally engaging the inner surface of the neck and normally cooperating with each other and with the inner surface of the neck to form a closed joint lying between the ends of the neck, said sections being provided with fluid outlets, and means connecting the sections for relative rotation whereby said outlets may be disposed in communication. ¹⁰
- 5 In testimony whereof I affix my signature.

MASON COMBS. [L.S.]
